UNITED STATES PATENT OFFICE.

FRANK C. SUCHY, OF SAN ANTONIO, TEXAS.

TAG-THREADING MACHINE.

1,343,290.

Specification of Letters Patent. Patented June 15, 1920.

Application filed May 31, 1919. Serial No. 300,925.

To all whom it may concern:

Be it known that I, FRANK C. SUCHY, a citizen of the United States, residing at San Antonio, in the county of Bexar and State 5 of Texas, have invented certain new and useful Improvements in Tag- Threading Machines; and I do hereby declare the following to be a full, clear, and exact description of the invention, such as will enable others 10 skilled in the art to which it appertains to make and use the same.

This invention relates to machines for threading cards, tags and the like with a flexible element such as ribbon, tape, cord 15 twine, etc., and has for its principal object the provision of means for inserting said flexible element through a hole in the card or tag and to remove the flexible element from the inserting means to leave the flexible 20 element in the card or tag.

Another object of the invention is the provision of means by which an imperforate card or tag may be perforated simultaneously with the operation of inserting the 25 flexible element in the perforation.

My invention will be described in detail hereinafter and illustrated in the accompanying drawings in which,

Figure 1 is a side view in elevation of my 30 improved machine,

Fig. 2 is a front view,

Fig. 3, a sectional view showing the ribbon in full lines before insertion through the card or tag, and in broken lines after 35 insertion,

Fig. 4, a detail view in section showing the needle in the position of inserting the ribbon through the card or tag and the picking mechanism about to remove the ribbon from 40 the needle,

Fig. 5, a fragmental view of the plunger showing the rear of the ribbon needle,

Fig. 6, a cross section of the needle on the plane indicated by the line 6—6 of Fig. 5,

Fig. 7, a fragmental view of the plunger showing the twine inserting needle in position,

Fig. 8, a cross section on the plane indicated by line 8—8 of Fig. 7, and

Fig. 9, a fragmental detail of the twine needle.

Referring to the drawings in which similar reference characters will be used to designate corresponding parts in the several 55 views, 1 indicates the base of my machine that is supported on depending integral

flanges 2, and having a hollow goose neck 3 extending upwardly therefrom, the hollow space in the goose neck communicating with the space under the base 1 for the purpose 60 hereinafter specified.

4 indicates a vertical cylindrical bearing on the end of goose neck 3 in which is slidably mounted a plungér 5 having a head 6 on its upper end, said plunger being held in 65 a raised position by means of a coil spring 7 mounted thereon and bearing against said head 6 and cylindrical bearing 4.

8 indicates a needle secured in a socket 8^a in plunger 5 and held therein by set screw 70 8^b, said needle being positioned to extend into an opening 9 in base 1 when the plunger is moved downwardly. Needle 8 is flat as shown and provided with flanges 10 on its rear side that are tapered to the point of the 75 needle for the purpose hereinafter specified. The point of the needle is formed with a central slot 11 and two prongs on each side of the slot, prongs 12 adjacent the slot being shorter than prongs 13 that form the sides 80 of the needle point.

14 indicates a shaft journaled in the side flanges on base 1, and having a lever 15 thereon to actuate it. 16 is an arm secured to shaft 14 and having its end provided with 85 a relatively thin and tapered finger 17 with a V-shaped notch 18 in its front face adjacent its end to form a pointed prong 19. Finger 17 is so positioned that when plunger 5 is moved downwardly, and needle 8 extends into opening 9, said finger will pass through slot 11 when shaft 14 is rocked forwardly.

20 indicates a spring that normally retracts arm 16, the rearward movement of 95 shaft 14 being limited by an arm 21 secured thereto engaging stop 22.

23 indicates a shaft to receive a spool 24 of ribbon, tape, twine or the like, and is held in position on the shaft by thumb nut 25. 100

26 indicates an opening in the front side of goose neck 3, 27 a loop guide secured to said goose neck adjacent the cylindrical bearing 4, and 28 a loop on the plunger in the rear of needle 8.

29 indicates a curved blade secured to the front side of bearing 4 by means of set screw 30, said set screw engaging a longitudinal groove 5^a in plunger 5 to prevent rotation thereof in bearing 4 and to limit the sliding 110 movement thereof.

31 indicates a guide plate secured to the

top of base 1 and spaced apart therefrom a sufficient distance to permit insertion of a tag or card between the base and plate, said plate being notched as at 32 over opening 9.

5 In operation the ribbon or tape on spool 24 is first threaded through goose neck 3, then out of opening 26 therein, and through loops 27 and 28. When a card or tag is to be ribboned the ribbon is held between 10 prongs 13 and against prongs 12.

10 The card or tag is inserted between base 1 and plate 31 and over opening 9. Plunger 5 is then actuated downwardly and needle 8 is pushed through the card or tag carrying 15 with it the ribbon impaled on prongs 12.

When plunger 5 reaches its lowermost position, the ribbon may be removed from 20 needle 8 by rocking shaft 14 by manually operating lever 15, this operation moving finger 17 through slot 11, and prong 19 by 25 engaging the ribbon will pull it off the needle and hold it through the opening in the card when the plunger is released to resume its original position.

25 The card or tag is then removed from under plate 31, the lever 15 having been released to resume its normal position, and the ribbon cut off at a suitable length on blade 29, the cutting being effected by manually 30 drawing the ribbon along the edge of said blade. As a general rule the movement of the ribbon in cutting it on blade 29 will re-impale it on prongs 12 in position for the next operation.

35 In Figs. 7, 8 and 9 is shown a needle that is utilized for inserting cord or twine through shipping tags. At the present time this operation is generally done by hand. The cord or twine is cut to proper length and 40 folded in its middle to form a loop. The loop is then inserted through the hole in a tag and the two ends of the cord or twine passed through the loop.

In my machine the spool or ball of cord 45 or twine is placed on shaft 23 and threaded through goose neck 3, and out of opening 26 therein. On the side of bearing 4 is a loop 33 through which the cord or twine is threaded.

50 34 indicates a needle for the cord or twine that is mounted in socket 35 in plunger 5 and held therein by means of a screw or other fastening means 34^a. Needle 34 is formed with two diametrically arranged 55 slots 36, 37, slot 36 being comparatively shallow and adapted to carry the cord or twine, while slot 37 is deeper than slot 36 and provided to receive finger 17 when the plunger is depressed to remove the cord or twine 60 from the needle. 38 indicates a longitudinal groove in each side of the needle and alining with slot 36 to receive the cord or twine.

The operation of the device in corded tags is substantially the same as that described for inserting ribbon through a card 65

or tag except that the tag has the hole therein and the needle shown in Figs. 7, 8 and 9 is not designed to form an opening in the tag but only to insert the twine through the hole in the tag. The tag is placed on the 70 base so that the hole therein alines with opening 9 in the base. Then by depressing plunger 5 needle 34 will carry the cord or twine held in slot 36 and grooves 38 through the opening. While in its lowermost position shaft 15 will be rocked to cause finger 17 to pass through slot 37 and the loop of cord or twine will be removed from the needle 34. The plunger 5 will then be released to return to its uppermost position and the tag with 80 the twine inserted therethrough removed from the base and the cord or twine cut off at a suitable length.

The particular details of my invention as described herein are capable of alteration 85 without changing the spirit of my invention so that I do not limit myself thereto except where limitations are the subject matter of the several claims hereinafter set forth.

Having thus described my invention what 90 I claim is.

1. In a tag threading machine, a base having a needle receiving opening therein, a plunger slidably supported above said base, a needle secured to said plunger, said needle 95 having prongs to engage a flexible tag threading element and a slot between said prongs, a shaft journaled on the base, an arm secured to the shaft, and a finger on said arm and adapted to operate through said 100 slot when the plunger is depressed to remove the flexible element from the needle.

2. In a tag threading machine, a base, a goose neck rising from said base, a bearing on said goose neck, a plunger slidably 105 mounted in said bearing, a needle secured to said plunger and formed to engage a flexible tag threading element, said base provided with an opening to receive said needle and flexible threading element, and means 110 mounted on said base to disengage the flexible elements from the needle when the plunger is in its lowermost position.

3. In a tag threading machine, a base, a goose neck rising from said base, a vertical 115 bearing on said goose neck, a plunger slidably mounted in said bearing, a spring to normally hold said plunger in a raised position, a needle secured to said plunger and formed to carry a flexible tag threading ele- 120 ment, said needle formed with a longitudinal slot, and an arm pivotally mounted and operating in said slot to release said flexible element from the needle.

4. A needle for tag threading machines 125 having a central longitudinal slot, two prongs on each side of said slot, the prongs adjacent the slots being shorter than the other prongs and adapted to engage a flat flexible tag threading element. 130

5. A needle for tag threading machines having a central longitudinal slot, side flanges on one side of said needle, the point of the needle comprising two prongs on each 5 side of the slot aforesaid, all of said prongs being alined, the prongs adjacent the slot being shorter than the prongs remote therefrom, the last mentioned prongs forming the edges of the needle point.
- 10 6. In a tag threading machine, a base having a needle opening therein, supporting flanges depending from said base, a goose neck extending upwardly from the base, a vertical slide bearing in said goose neck, a plunger slidably mounted in said bearing, a needle secured to said plunger and having a longitudinal slot therein, two prongs on each side of said slot and forming the point of the needle, one of each pair of prongs 15 forming the outer edge of the needle point, the other prongs being shorter than the outer prongs and adapted to engage the tag threading element, a shaft journaled on the base flanges, an arm on said shaft, and a finger on said arm adapted to operate in the slot in the needle to remove said flexible element therefrom.
- 20 7. In a tag threading machine, a base having a needle opening therein, supporting flanges depending from said base, a goose neck extending upwardly from the base, a vertical slide bearing in said goose neck, a plunger slidably mounted in said bearing, a needle secured to said plunger and having a longitudinal slot therein, two prongs on each side of said slot and forming the point of the needle, one of each pair of prongs 25 forming the outer edge of the needle point, the other prongs being shorter than the outer prongs and adapted to engage the tag threading element, a shaft journaled on the base flanges, an arm on said shaft, and a finger on said arm adapted to operate in the slot in the needle to remove said flexible element therefrom.

7. In a tag threading machine, a base hav-

ing a needle opening therein, supporting flanges depending from said base, a goose neck extending upwardly from the base, a vertical slide bearing in said goose neck, a plunger slidably mounted in said bearing, a needle secured to said plunger and having a longitudinal slot therein, two prongs on each side of said slot and forming the point of the needle, one of each pair of prongs forming the outer edge of the needle point, the other prongs being shorter than the outer prongs and adapted to engage the tag threading element, a flange on each longitudinal edge of one side of the needle to receive said tag threading element, a shaft journaled on the base flanges, an arm on said shaft, and a finger on said arm adapted to operate in the slot in the needle to remove the flexible element therefrom, said finger having a V-shaped notch in its engaging face and forming a hook on the end thereof.

In testimony whereof I affix my signature 50
in presence of two witnesses.

FRANK C. SUCHY.
